Inventor:

Francis H. Richards.

UNITED STATES PATENT OFFICE.

FRANCIS H. RICHARDS, OF HARTFORD, ASSIGNOR TO THE TRAUT & HINE MANUFACTURING COMPANY, OF NEW BRITAIN, CONNECTICUT.

SUSPENDER-BUCKLE.

SPECIFICATION forming part of Letters Patent No. 436,262, dated September 9, 1890.

Application filed May 1, 1890. Serial No. 350,240. (No model.)

To all whom it may concern:

Be it known that I, FRANCIS H. RICHARDS, a citizen of the United States, residing at Hartford, in the county of Hartford and State 5 of Connecticut, have invented certain new and useful Improvements in Suspender-Buckles, of which the following is a specification.

This invention relates to buckles for suspenders, and to that class of said buckles having "cast-offs," the object being to provide a buckle of that class which shall be simple in construction, cheaply manufactured, and readily operated.

15 The invention consists in the improvements hereinafter more fully set forth.

In the drawings accompanying and forming a part of this specification, Figure 1 is a front or side view of a suspender-buckle embodying my improvements. Fig. 2 is an edge view of the buckle, drawn in projection with Fig. 1. Fig. 3 is a vertical section through the box. Fig. 4 is a front view of the "box-plate." Fig. 5 is a sectional detail view showing a feature of the pivot construction. Fig. 6 is a plan view of the inside of the lever-plate. Fig. 7 is a front or side view of a modification of the buckle, from which some of the features shown in the preceding figures are omitted. Fig. 8 is an edge view of the form of buckle shown in Fig. 7. Fig. 9 is a section of the buckle-plate in line *a a*, Fig. 7. Fig. 10 is a view of the hanger removed from the buckle.

25 Similar characters designate like parts in all the figures.

The box or plate B, Figs. 1 to 5, inclusive, consists of the buckle-plate 22, the edge walls 20 20, and the inwardly-projecting front 40 plates 24 24, having the notches 21 21, constituting a part of the pivot construction. The "lever" or front plate L in said Figs. 1 to 5 consists of the lever-plate 25, having the end 26 abruptly bent, as shown, and having the 45 notches 23 23 at the ends of the angle of the said bend. By this means the said plates interlock, as indicated in Figs. 1 to 6, inclusive, to form a joint allowing the lever to turn approximately through the one-fourth part of a 50 circle. In the top plates 24 24 there are formed

suitable catches, as 32 34, which stand above the line of the plate 25, for receiving the corresponding hooks of the hanger.

The hanger or strap-supporting member S consists of a depending elastic central loop 55 formed of the sides 16 and 18, connected at their lower ends by the loop or bend 29, to which the middle strap 15 may be attached. Intermediate of its length the hanger has formed in the sides thereof the inclined portions or strap-carrying bars 12 and 14, to which are attached the usual suspender-straps 11 and 13, respectively, by any convenient means or method. At their upper ends said sides 16 and 18 have formed thereon the oppositely-disposed hooks 28 30, which engage the aforesaid correspondingly-formed catches 32 34, formed in the box front walls or plates 24 24. When engaging with said catches, the upper ends of the hanger S lie 60 close over the lever-plate 25, and thus securely locking said lever L closed, as shown in Figs. 1 and 2.

When the cast-off feature of the buckle is to be used, the user grasps the hanger by the 75 upper ends and closes together the sides thereof until its said hooks disengage from the catches; when the hanger may be taken off, thereby completing the separation of the two principal parts of the suspender. This releases the lever L, so that it may be operated 80 for unlocking the box B from the web for the purpose of adjusting the length of the suspender.

In the modification shown in Figs. 7, 8, and 85 9 the buckle-plate B is of the particular kind described and shown in my application, Serial No. 350,237, filed May 1, 1890, with the exception that in the present case there is no separate "suspension-hook 10," as in that application. Said buckle-plate B is provided 90 with the usual holding-teeth, as 7, Fig. 3, for engaging the web 3 of the suspender, with means, as the lever L, carried on pivots 4 4, formed on the plate, for clamping the web 3 95 in engagement with said teeth to secure the plate to said web, and with means for carrying the elastic hanger S, said means consisting in the aforesaid oppositely-disposed catches 32 34, substantially the same as those 100

formed in the box-plate B, Figs. 1 to 4, inclusive.

It will be observed that the hanger sides 16 and 18 above the bars 12 14, Fig. 7, may 5 both be upwardly and inwardly directed, so that the straps 11 and 13 draw on the hooks 28 30 downwardly and outwardly, thereby holding them firmly in place.

The operation of the cast-off feature of the 10 form of buckle shown in Figs. 7 and 8 is the same as above described.

Having thus described my invention, I claim—

1. In a buckle, the combination, with the 15 buckle-plate having two oppositely-disposed hanger-supporting catches at its sides, of the depending hanger consisting of a single piece of wire bent in its middle portion to form a U-shaped loop, the diagonal bars for the sus- 20 pender-ends, and two spring-arms with hooks for engaging said buckle-plate catches, respectively, substantially as described.

2. In a buckle, the combination, with a 25 buckle-plate, substantially as described, having the oppositely-disposed hanger-supporting catches, of the depending strap-carrying hanger having its ends terminated with op-

positely-disposed hooks constructed to engage said catches, having its depending lower part shaped to carry a strap, and having its sides 30 intermediate of their length shaped to form the oppositely-disposed strap-carrying bars 12 and 14, respectively.

3. In a buckle, the combination, with the box-plate and the lever-plate pivotally connected, said box-plate having the catches 32 and 34, of the hanger having hooks engaging said catches, said hook-provided ends of the hanger lying over the lever-plate and locking the same closed.

4. In a buckle, the combination, with the box having the back plate, the end walls, and the front plates inwardly projecting from said walls, and having the notches 21 21 formed therein, of the lever L, having notches 23 23 and interlocked with said front walls of the box, the hanger-supporting catches on said front walls, and a strap-carrying hanger, substantially as described, engaging said catches and locking closed said lever.

FRANCIS H. RICHARDS.
